CARRY FOIL MECHANISM

Joseph A. V. Turck, Wilmette, Ill., assignor to Felt
and Tarrant Manufacturing Company, Chi-
cago, Ill., a corporation of Illinois

Application September 21, 1940, Serial No. 357,677

19 Claims. (Cl. 235—82)

This invention relates in general to calculating machines and, while it is illustrated herein as being incorporated in a machine similar to that disclosed in my prior United States Letters Patent No. 2,063,962, issued December 15, 1936, it will be readily appreciated that the invention has other and more general valuable applications.

In calculating machines of the type shown in said patent, and generally in substantially all machines having actuating mechanism adapted to drive the registering or accumulating mechanism in only one direction, subtraction is performed by a process of complementary addition. For example, if it is desired to subtract "127" from the number "824," the latter is registered in the numeral wheels of the accumulator, and the nine's complement of the subtrahend less one, or the ten's complement of the units order and the nine's complement of all other orders of the subtrahend, namely, "873," is added to the minuend. This would normally leave a result of "1697" in the accumulator. In certain of the prior art machines, such as those disclosed in the patents to D. E. Felt, No. 767,107 and No. 960,528, issued on August 9, 1904, and June 7, 1910, respectively, a subtraction or carry cut-out lever is provided in association with each denominational order of accumulator mechanism, except the units order, which is selectively operable to prevent a transfer or a carry of the tens thereto. These subtraction levers are manually operable, and must be held in operative position in order to prevent a transfer to the associated order of accumulator mechanism. In performing the above problem on such a machine, by actuating the subtraction lever in that order to the left of the first figure of the subtrahend and manually retaining the same in operative position, the carrying of the tens to such order of the accumulator is prevented, and the correct result, "697," will appear on the numeral wheels of the accumulator. Means are provided in the patent to C. Wittenmyer, No. 1,840,378, issued on January 12, 1932, for locking such subtraction levers in operative or carry foiling position, and for automatically unlocking the same to permit the return thereof to inoperative position only after a carry has been attempted and foiled thereby. However, it is still incumbent upon the operator to select the proper subtraction lever to be operated in any given instance, and to move only that particular lever to operative position.

A principal object of this invention, therefore, is the provision in such a calculating machine of means for relieving the operator of the responsibility and effort of selecting one of a plurality of

subtraction levers in order to foil undesired carrying of tens.

Another important object of the invention is the provision of means in a calculating machine for automatically foiling the undesired carry of the tens to that order of the accumulator mechanism next higher than the highest order of the minuend, in a subtractive operation, by depression of a single key, as well as the elimination of the manipulative means heretofore necessary to accomplish the desired result.

A further important object of the invention is the provision of a subtraction control key which, when depressed, causes the carry of the tens to the next higher order of the accumulator to be automatically and positively prevented upon subsequent depression of any digital key representing the first or left hand figure of the subtrahend.

Another important object of the invention is the provision of means for automatically latching the carry transfer means in the proper denominational order, and for automatically releasing the same after a carry has been attempted and foiled.

A further important object of the invention is the provision of means for automatically releasing such carry transfer foiling means whenever the accumulator is zeroized.

Another important object of the invention is the provision of means for automatically re-conditioning the machine for additive actuation after a subtractive operation has taken place.

A further object of the invention is the provision of means for preventing the setting of the carry transfer foiling means during operation of the additive actuating mechanism of the machine.

Another object of the invention is the provision of means for preventing the operation of the carry transfer foiling means during zeroizing of the accumulator.

Numerous other objects and advantages of the invention will be apparent as it is better understood from the following description, which, when taken in connection with the accompanying drawings, discloses a preferred embodiment thereof.

In the drawings,

Figure 1 is a top plan view, broken away centrally from front to back, of a calculating machine embodying the features of my invention, and showing the "add" and "subtract" keys located to the left of the ordinal series of digital keys;

Figure 2 is a front to back vertical section

taken through the calculating machine shown in Fig. 1 on a plane arranged alongside a column or order of digital keys, with parts broken away;

Figure 3 is a fragmentary elevational view of the mechanism for controlling the operation of the carry cut-out levers;

Figure 4 is a perspective view of a carry cut-out or subtraction lever and associated parts;

Figure 5 is a fragmentary elevational view of the accumulator zeroizing means and the carry transfer lock releasing means; and

Figure 6 is a fragmentary elevational view of the carrying pawl latch releasing means.

For the purpose of illustrating my invention, I have shown in the drawings a key-responsive, power operated calculating machine similar to that shown and described in Patent No. 2,063,962, hereinbefore referred to. Referring more particularly to the drawings, the calculating machine is shown as having an outer casing 21 within which the various instrumentalities of the machine are mounted on skeleton frame members or partition plates 22 (Fig. 2) disposed between the actuating mechanisms of the several denominational orders and secured together in spaced relationship at suitable points by tie-rods 23. A plurality of columns of digital keys 24 are arranged to extend through a keyboard 25, positioned as part of the upper wall of the casing 21, which keys are adapted for manipulation to determine the digital degree of actuation to be imparted to the different denominational orders of a multiple order accumulator mechanism. Each column of keys controls the rotation of an accumulator actuating pinion 26 (shown in broken lines in Fig. 2) journaled upon a transverse shaft 27 that extends across the machine and is supported by the frame members 22. Rotation of each of the actuating pinions 26 is transmitted through an internal ratchet mechanism to a combined lantern wheel and accumulator gear 28 which is also journaled on the shaft 27. The gear of the lantern wheel 28 meshes with a carrying gear, sometimes called the carrying spring winding gear (not shown), journaled on a shaft 29, which is disposed in parallel relationship to the shaft 27. The carrying gear also meshes with an intermediate gear 31 journaled on a transverse shaft 32, which in turn meshes with a numeral wheel pinion 33 journaled on a transverse shaft 34 and fixed to a numeral wheel 35.

Carrying mechanism is provided in each denominational order of the accumulator mechanism for the purpose of imparting a digital unit of actuation thereto each time that a tens transfer is to take place from the next lower denominational order of the accumulator. This mechanism, as well as that hereinbefore described, is more fully disclosed in United States Letters Patent No. 1,357,747 and No. 1,357,748, issued on November 2, 1920, and includes a carrying-cam member 36, which is given a 180° rotation by a suitable carrying motor spring 37 associated with the carrying gear of the next lower denominational order for each tens transfer that is to be effected. The carrying-cam member 36 acts upon a dolly roll 38 secured to a bell crank carrying-lever 39 to swing the latter in a clockwise direction, viewing Fig. 2. Such swinging of the carrying-lever 39 causes a carrying pawl 41 pivotally mounted on said lever to throw the lantern wheel and accumulator gear 28 a sufficient distance to impart, through the train of gears, a digital unit of actuation to the numeral wheel 35.

The adding is accomplished upon depression of the keys 24 and corresponding actuation of rack sectors 42 which are in mesh with the pinions 26, a said sector being associated with each denominational section of the accumulator unit in association with its controlling column of keys. The rack sectors and the control and actuating mechanisms for them are duplicated for each denominational order of the calculating machine, and a general description of a single set of such mechanism will be sufficient for an understanding of them all, except that they have to be arranged and adapted to cooperate selectively and collectively with the power members.

The rack sectors 42 are mounted upon a shaft 43 which extends through the partition plates 22 of the machine, and are adapted to be moved downwardly (viewing Fig. 2) on an idle or setting stroke in amount determined by the value of the particular digital key 24 of the associated column depressed, this amount increasing in graduating steps from one to nine. Upon depression of any key 24, power is supplied by an electric motor, indicated generally at 44 (Fig. 2), through a power shaft 45, which is connected to the motor in any suitable manner, to extend a spring 46 associated with the particular order of mechanism with which the key depressed is identified, release of this spring thereafter accomplishing adding movement in amount determined by the particular key of the order depressed. Upon depression of said key, the rack segment 42 is moved through its idle or downward stroke by the power shaft 45 into position to impart proper and accurate digital accumulation to the adding mechanism upon its return movement, which is accomplished by the associated spring 46.

In the calculating machine shown in the drawings, depression of a key 24 causes its stem 47 to engage a parallel motion bar 48 which is pivoted at the front at 49 and at the rear at 51 to levers 52 and 53, which levers are pivoted in turn upon cross shafts or rods 54 extending through the partition plates 22. A link 55 is pivotally connected at 56 to the lever 52 and at 57 to the lever 53. The bar 48, levers 52 and 53 and the link 55 form part of a parallel motion device and are constructed and mounted as shown and described in United States Letters Patent No. 2,063,962, earlier mentioned. Further and more particular description of these parts is therefore thought to be unnecessary. Each of the rack sectors 42, as stated above, is pivoted upon the cross shaft 43, and is respectively connected to a hook 58 by a link 59, and to a movement controlling bar 61 by a link 62 (Fig. 2), the former said connection being through a compensating device 63. The operation of the parts is such that upon depression of a key 24, the stem 47 engages and depresses the bar 48, imparting motion to the parallel motion device, and through suitable control mechanism which it is thought need not be described herein in detail, but includes a dog 64 pivoted on the bar 48, moving the hook 58 down into engagement with a toothed wheel 65 which is fastened to the power shaft 45. The engagement of the hook 58 with the wheel 65 pulls the link 59 toward the left, viewing Fig. 2, which imparts downward motion to rack sector 42 and link 62 through the compensating device 63. Forward motion is thus imparted to the digital control bar 61, until one of several lugs projecting laterally therefrom is stopped by the stem 47 of the key 24 depressed.

The link 59 extends the spring 46, and moves the rack sector 42 downwardly on an idle stroke and into position to impart an adding movement upon release of the hook 58 and contraction of the spring. The downward movement of the rack sector 42 is under the control of the digital control bar 61, and the rack sector is halted when it has been moved downwardly the proper distance, enabling it upon return to impart the degree of digital advancement to the adding mechanism which corresponds to the particular key depressed. The compensating device 63 permits the continuation of the rearward movement of the link 59 after downward movement of the rack sector 42 has been stopped, and until the end of the power stroke and the automatic release of the hook 58. The release of the hook 58 is accomplished automatically in each instance, after a set increment of action has been imparted to the link 59, by the teeth of the wheel 65. Upon the return stroke (the operative stroke of the rack sector), the compensating device 63 permits movement of the parts in reverse direction to the beginning of the adding movement and thereafter the adding actuation is accomplished.

It is apparent, therefore, that upon depression of a key 24, the digital control bar 61 determines the degree and extent of the downward movement of the rack sector 42, and the bar 48 initiates the connection of the rack sector to the power mechanism. In this operation, the key 24 which has been operated is held depressed until release of the hook 58 from the wheel 65, when the key will be released and returned to normal raised position. It will be understood that, while no two keys 24 of the same column or denominational order may be operated simultaneously, any key of one order may be operated at the same time as any desired key of any other denominational order or orders.

The accumulator is adapted to be cleared or zeroized by interrupting the connections between the numeral wheels and the actuating mechanism therefor. More particularly, zeroizing is effected by detraining or disengaging the carrying spring winding gears from the accumulator actuating pinions 26. To this end, the shafts 27, 32 and 34 are mounted in and supported by the skeleton frame members 22. The shaft 29 of the carrying spring winding gears, however, is mounted in a swinging frame that is adapted to have a slight outward or forward pivotal movement (to the right in Fig. 2) on an axis coincident with the shaft 32. This swinging frame is made up of a plurality of partition plates 66 connected together at suitable points by transverse tie-rods 67.

As the swinging frame carries the shaft 29 of the carrying spring winding gears, the latter are disengaged from the pinions 26 whenever the frame is swung to the right of its normal position of Fig. 2. Such swinging of said frame is accomplished by a short clockwise rocking movement (viewing Fig. 2) of a transverse shaft 68 that is journaled in the fixed skeleton frame members 22. Rocker arms 69 (only one of which is shown in Fig. 2) are fixed at one end on the shaft 68, and are pivotally connected at their other ends to curved links 71 having slotted shifting pivots upon a fixed transverse shaft 72. The forward end of each link 71 is provided with a pin 73 positioned within the spaced jaws of a bifurcated member 74. The member 74 is pivoted intermediate its ends on a shaft 75 carried by the swinging frame hereinbefore described, and comprises the inner mem-

ber of a toggle. The outer member of the toggle comprises a bell crank 76 pivotally connected at its inner end to the member 74 and pivoted intermediate its ends on a stud 77 mounted on the associated fixed frame member 22. Consequently, rocking of the shaft 68 in a clockwise direction from its normal position of Fig. 2 shifts the curved links 71 toward the front of the machine by means of the arms 69. This causes the pins 73 to push down on the lower jaws of the inner ends of the toggle members 74, thereby throwing the toggles past their dead centers. Since the toggle members 74 are pivoted at 75 to the aforesaid swinging frame, such movement of the toggles is accompanied by an outward swinging of the swinging frame to detrain the carrying spring winding gears from the actuating pinions 26.

To impart such rocking movement to the shaft 68, there is provided a short transverse shaft 78 (Fig. 5) that extends through the outer casing of the machine and has an operating handle or zeroizing lever 79 secured thereto. A segment 81 is fixed upon the inner end of shaft 78, and pivoted to the segment is a link 82, which is in turn pivoted to a depending lever 83 that is pivoted at 84 on the fixed frame of the machine. The lower end of lever arm 83 is pivotally connected by a short link 85 with an arm 86 mounted on the shaft 68. A short swinging movement of crank 79 to the right, viewing Fig. 5, will, through segment 81, link 82, lever arm 83, short link 85, and arm 86, impart such movement to the shaft 68 as is necessary to detrain or disengage the aforesaid to effect zeroizing of the accumulator. A more detailed description of the zeroizing mechanism is not thought to be necessary to a clear understanding of the instant invention, reference being hereby made to Patent No. 1,357,748, hereinbefore cited, and Patent No. 1,902,597, issued on March 21, 1933, for such a description.

The present invention provides for calculating machines of the type above described, a novel subtracting mechanism which relieves the operator of certain responsibilities and work heretofore required in the performance of a subtractive operation. For accomplishing this work, the subtracting mechanism has a plurality of carry cut-out or disabling devices, one individual to each denominational order of the accumulator and adapted when operated to disable the tens carrying mechanism of the order. The devices are normally disposed in an inactive position but are arranged to be shifted conjointly and simultaneously to an active position by operation of common manipulative means such as a key to condition the devices for individual operation by the actuation of any selected digital key in the same order. Thus by simply setting the manipulative means before actuating the digital key to register the first or left hand figure of the subtrahend, the carrying of tens to the next higher denominational order of the accumulator is effectually prevented.

In the particular embodiment illustrated, the disabling devices operate to prevent the undesired carrying of tens by moving the appropriate carrying pawl 41 out of its normal position into an inactive position and latching it there throughout the ensuing adding cycle of the machine. The latched pawl is automatically released after a carry has been attempted and foiled and as an incident to such attempt thereby conditioning the machine for an additive operation. When no carry is attempted, the clearing or zeroizing of the machine releases the latched carrying pawl.

As herein shown (Figs. 1 and 3), the common

manipulative means for conditioning the disabling devices comprises a set of keys including "add" and "subtract" control keys 87 and 88, respectively, located at the left of the ordinal series of keys 24 for convenient access. The keys are provided with the usual stems 89 extending through the keyboard 25 and connected in any suitable manner to opposite ends of a walking-beam lever 91 journaled on a short rod 92 carried by the frame of the machine. Pivotally secured to the lower end of the walking-beam lever 91 is a connecting link 93, the opposite end of which is pivotally secured to an upwardly extending arm 94 mounted on a bushing journaled on a transverse shaft 95. Fixed to the shaft 95 is a segment plate 96 provided with a slot 97 for the reception of a stud 98 mounted on the arm 94. The stud 98 is normally held in rearwardly engaging position with the slot 97, as shown in Fig. 3, under tension of a spring 99 connected to arm 94 at 101 and to plate 96 at 102.

From the above arrangement it will be apparent that depression of either key 87 or 88 will, by means of walking-beam lever 91, link 93 and arm 94, cause rocking of the shaft 95. The shaft 95 is maintained in either position to which it is so rocked by means of a yieldable detent 103 journaled on a transverse shaft 104 and provided with a stud 105 adapted to engage V-notches 106 in the upper surface of the segment plate 96. The detent stud is resiliently maintained in engagement with either one of the notches 106 in the plate 96 under tension of a spring 107, until moved out of engagement therewith and into engagement with the other notch 106 by rocking of the shaft 95 and the plate 96. Rocking movement of the shaft 95 in a clockwise direction, viewing Fig. 3, is limited by engagement of a stop arm 108 on the plate 96 with a stud 109 mounted upon one of the intermediate frame members 22, and counter-clockwise movement of the shaft 95 is limited by engagement of a stop arm 111 on the plate 96 with one of the frame tie-rods 23.

The rocking movements of the shaft 95 act to shift the disabling devices of the various denominational orders between active and inactive positions. For this purpose, an arm 112 is fixed to the shaft 95 in association with each denominational order of the machine. Each arm is connected by a vertical link 113 with one member of the associated disabling device which, in this instance, comprises a curved link 114 pivotally mounted on a depending arm 115 of a lever 116 comprising another member of the device and conveniently called the subtraction or carry cut-out lever. Formed on each link 114 is a shoulder 117, which is adapted to be moved into the path of a lateral projection 118, formed on the forward end of each link 55, when the shaft 95 is rocked in a clockwise direction from its normal position of Figs. 2 and 4, upon depression of key 88. From the construction and arrangement of the parts just described, it will be apparent that depression of the subtraction control key 88 will cause rocking of the walking-beam lever 91 in a counter-clockwise direction, viewing Fig. 3. Such motion of the walking-beam lever 91 is transmitted through pivotally connected link 93 to arm 94, thus causing clockwise rotation of shaft 95 through the tensioning of spring 99 to overcome the detaining action of detent 103. This movement continues until halted by arm 106 of segment 96 contacting stud 109. This

movement of the shaft 95 conditions the disabling devices for operation by imparting vertical movement to the links 113, whereby shoulders 117 of links 114 are disposed in the path of the lateral projections 118 on the links 55. The parts are resiliently maintained in this position by the detent 103.

The above mechanism also prevents rocking of the shaft 95 by depression of key 88 when link 55 of the parallel motion device of any denominational order is in a forward position in response to depression of a key 24. When the link 55 is in a forward position due to depression of any of its associated keys 24, projection 118 is disposed immediately above shoulder 117 on the associated link 114, and vertical upward movement of the link 113 connected thereto is restrained. The arm 94, however, is permitted limited movement with respect to segment 96, through the pin and slot connection 98, 97 therebetween. Consequently, tension set up in spring 99 by clockwise movement of arm 94 in the depression of subtraction control key 88 returns these parts to their normal position of Fig. 3 when the key 88 is released, whenever any link 55 is in its forward or operative position.

The carry cut-out lever 116 of the disabling device in each denominational order is pivotally supported upon a cross shaft 119 extending through the main frame plates 22, and is provided with a lower end portion 121 (Figs. 2 and 4) curving forwardly and terminating in a tail which engages under a lateral extension 122 on the forward end of the carrying pawl 41. In the normal position of the parts shown in Fig. 2, this forwardly extending tail portion 121 of the lever 116 will not interfere with the rearward and upward movement of the carrying pawl 41 in the swinging of the carrying lever 39 to impart a carrying impulse to the lantern wheel 28. When it is desired that a subtractive operation be performed, however, the subtraction control key 88 is depressed, rocking the shaft 95 and disposing the shoulders 117 of all the links 114 in the path of the lateral projections 118 on their associated links 55. Upon depression of an ordinal key 24 movement is imparted to the parallel motion device in that order, as previously described, and the link 55 of the said order is moved forwardly, or to the right in Fig. 2. Upon forward movement of the actuated link 55, the projection 118 thereon engages shoulder 117 on the associated link 114 to move the latter forward, thereby swinging the associated subtraction lever 116 which projects over into the next higher order in a counter-clockwise direction a very short distance from its normal position of Fig. 2. This forward movement of the subtraction lever 116 tensions a spring 123 which is connected between the upper end of the lever and a main frame plate 22, and normally tends to maintain the lever 116 in its normal position of Fig. 2. When so moved to its forward position by the associated link 55, the upper surface of the forwardly extending tail portion 121 of the lever 116 engages the lateral extension 122 to lift the forward end of the carrying pawl 41 of the next higher denominational order and swing the latter in a counter-clockwise direction (Fig. 2) into inoperative position, where it is adapted to be held until released by the rearward motion of the carrying lever in a carrying operation, as will be later described.

The first ordinal key actuated in registration of the subtrahend determines the order in which

the carry cut-out mechanism is to function. It will be understood that in practice the first key actuated for this purpose is a key in the order corresponding to the first figure of the subtrahend when that figure is of a lower value than the figure of the corresponding order of the minuend or when both subtrahend and minuend are of the same order. When the subtrahend has a less number of figures than the minuend and the first figure is of a value such that "borrowing" from a higher order or orders of the minuend is necessary the "zero" key (small figures) in each of such higher orders is actuated before the subtrahend is entered. To insure selection of the carry cut-out mechanism of the correct order in either case, the key of the highest order to be actuated should complete its stroke before the key in any lower order is depressed sufficiently to trip its associated cut-out mechanism.

Means are provided for conditioning the machine for subsequent additive actuation by returning all of the carry cut-out levers 116 and associated parts to their normal position of Fig. 2, after the selected carrying pawl 41 has thus been moved to inoperative or carry foiling position and before the carrying operation takes place. For this purpose, a stud 124 is mounted on the forward end of each of the links 59, each one of which, as previously described, is pulled toward the left, viewing Fig. 2, upon engagement of its associated hook member 58 with the related toothed wheel 65 upon depression of a key 24. As one of the links 59 moves rearwardly (to the left in Fig. 2) in response to depression of the key 24 representing the first figure of the subtrahend, stud 124 engages the arm 112 in the corresponding denominational order, which is fixedly secured to the shaft 95, and swings it in a counter-clockwise direction, rocking shaft 95 to the normal position shown in Fig. 2, where it is maintained by engagement of the stud 105 in the forward notch 106 under tension of spring 107. This rocking movement of the shaft 95 pulls all the links 114 downward from their active to their inactive positions thereby withdrawing the shoulders 117 from the path of the projections 118, which allows the set carry cut-out lever 116 to return to its normal position of Fig. 2 under contraction of its spring 123. Thus, the carry cut-out lever 116 which has been moved to operative position is returned to normal inoperative position at the end of the downward movement of the associated rack sector 42, and before accumulative action takes place upon the return movement of the rack sector and any resultant rearward swinging of the carrying lever 39 in a carrying operation.

Such automatic return movement of the shaft 95 to its normal position of Figs. 2 and 3 also functions to return the members 96, 94, 93 and 91, and the "add" and "subtract" keys 87 and 88 to their normal positions of Fig. 3. It will also be appreciated that all of the carry cut-out levers 116 and their associated parts may be selectively returned to their normal or inoperative positions of the drawings after the subtraction control key 88 has been depressed, and before depression of any ordinal key 24, merely by depressing the "add" key 87.

Means is provided for latching the carrying pawl 41 in an inoperative position before and during the carry transfer operation, and for automatically releasing it after the carry has been foiled. As already described, engagement of the curved tail portion 121 of the carry cut-out lever

116 with the carrying pawl 41 rocks the rearward end of the carrying pawl downward, thereby allowing a lateral extension 125 thereon (Fig. 2) to engage under a shoulder 126 provided on a latch 127 pivotally mounted on the carrying lever 39. The latch 127 is resiliently held in engagement with the lateral extension 125 of the carrying pawl under tension of a spring 128 to hold the carrying pawl in such inoperative position. Consequently, rearward movement of the upper end of the carrying pawl 41 will be below the pins of the lantern wheel gear 28 when the carry transfer lever 39 is swung rearward in a carrying operation, and the carry which would normally take place by such movement of the carrying pawl will be foiled.

The rearward swing of the carry transfer lever 39 in such an attempted and foiled carrying operation is utilized to release the latch and allow the carrying pawl 41 to return to its normal position after the pawl has passed the pin of the lantern wheel gear 28 it would normally engage to produce a carry. This is accomplished by means of an arm 131, one of which is securely fixed to a transverse shaft 132 in each denominational order of the machine, which are normally maintained in the rearward position of Figs. 2 and 6 by a spring 133 connected at one end to a spring arm 134 and at the other end to a transverse shaft 135, as shown in Fig. 6. A lateral extension 136 (Fig. 6) is formed on the upper end of each arm 131 which is disposed in the path of a lower extension 137 (Fig. 2) of the associated latch 127. As the carrying lever 39 swings rearward in the carrying operation earlier described, the lower extension 137 of the latch 127 contacts the lateral extension 136 formed on the arm 131 and, as the carrying lever 39 continues its rearward movement, the lateral extension 125 on the carrying pawl 41 rides from under the shoulder 126 on the latch 127 allowing the rearward end of the carrying pawl 41 to rise to its normal operative position of Fig. 2, where it is maintained during the return movement of the carry transfer lever 39.

In the event that a carrying pawl 41 were inadvertently latched up by erroneously depressing the subtraction control key 88 and an ordinal key 24, it will be apparent that the result of the subsequent calculation would be incorrect, unless means are provided for releasing the latch 127 thus made operative. It is the usual practice for the operator, before beginning a calculation or after an error has been made, to clear or zeroize the numeral wheels. Therefore, releasing means are provided to act coincident with the zeroizing operation to return the parts to their normal inoperative position of the drawings for additive actuation. This releasing function is accomplished through the forward movement of the zeroizing lever 79 and its associated lever 83 which is pivotally connected by means of a slotted link 137 (Fig. 5) to a stud 138 mounted on an upright arm 139 fast on the shaft 132. As the lever 83 is moved forwardly upon operation of the zeroizing lever 79 (to the right in Fig. 5), the rearward portion of the slot in link 137 engages the stud 138 and rocks the shaft 132 in a clockwise direction. As has been previously described, the shaft 132 is provided with arms 131 fixedly secured thereto. Forward or clockwise rotation of the shaft 132 and arms 131, therefore, will cause the lateral projection 136 of an arm 131 to contact a shoulder portion 141 (Fig. 2) on the latch 127 which has been

moved to operative position, and urge the latch forwardly or to the right, viewing Fig. 2, to disengage the shoulder 126 from the lateral projection 125 on the carrying pawl 41. It will be noted from Fig. 5 that rocking movements of the shaft 132 are limited by the ends of a lower bifurcated portion 142 of the arm 139, which is fixed to said shaft, contacting a transverse shaft 143, the spring 133 shown in Fig. 6 normally retaining the arm 139 in the position of Fig. 5.

Coincident with the above-described releasing action of a set latch 127, rocking movement of the shaft 88 in a zeroizing operation is also utilized to rock the shaft 95 in a rearward or counter-clockwise direction (viewing Fig. 5) to return the links 113 and 114 to their normal inoperative position of the drawings, thus removing the shoulders 117 from the paths of the projections 118 on the links 55, providing they have been left set inadvertently. A stud 144 (Fig. 5) is provided in the lower portion of the arm 86 to contact an arm 145 fast to the shaft 95, when the shaft 88 is rocked in a forward direction. This engagement of the stud 144 with arm 145 results in counter-clockwise rotation of the shaft 95, which movement is transmitted through arms 112 and links 113 to remove shoulders 117 of links 114 from the paths of lateral projections 118 when links 55 are moved forwardly in response to the depression of ordinal keys 24.

It will be apparent that rocking of the shaft 95 cannot be accomplished by depression of key 88 when the zeroizing lever 79 is in a forward position and stud 144 is in engagement with the arm 145. In order to prevent bending and twisting of the parts, if it is attempted to forcibly depress the subtraction control key 88 under such conditions, the shaft 95 is given limited movement, as already described, through engagement of stud 98 of arm 94 in slot 97 of the segment 96. Tension set up in spring 99 by such limited movement resulting from depression of key 88 returns the parts to the normal position of Fig. 3 when the key 88 is released.

It is thought that the invention and its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim as my invention:

1. In a calculating machine having a series of denominational orders of accumulator mechanism including automatic tens carrying mechanism, actuating mechanism for said accumulator, and depressible keys for effecting operation of said actuating mechanism; normally inoperative means adapted to be operated in response to the depression of any one of said keys for preventing effective operation of a selected tens carrying mechanism, said means being normally incapable of operation by the keys, and manipulative means for rendering said means operable by the keys.

2. A calculating machine having, in combination, a multiple order accumulator mechanism including automatic carrying mechanism, actuating mechanism for each order operable to actuate the corresponding order of the accumulator in variable degrees of actuation, a denominational order of keys for the actuating

mechanism of each order operable to determine the digital setting of the mechanism, subtraction mechanism including a disabling device individually associated with each order of accumulator mechanism operable to disable the carrying mechanism of its order to prevent a carry of tens to the next higher order, each of said disabling devices having one position in which it is inactive, another position in which it is set for operation, and a third position in which it acts to disable the carrying mechanism of the order, subtraction control means manually operable to shift all of said devices simultaneously from their inactive to their set positions, means responsive to the actuation of any key of one of said denominational orders for operating the disabling device of that order from its set position to its disabling position, and other means operative upon the depression of said key to restore the disabling devices to their inactive positions.

3. In a calculating machine having a series of denominational orders of accumulator mechanism including carrying mechanism for transferring the tens from a lower to a higher denominational order, actuating mechanism for said accumulator mechanism, and depressible keys for controlling the operation of said actuating mechanism; means for disabling said carrying mechanisms, normally inoperative means connected to said disabling means, and means for positioning said last means for operation to disable a said carrying mechanism upon depression of a said key.

35 4. In a calculating machine having an accumulator including tens transfer devices, an actuating mechanism for said accumulator mechanism, and keys for controlling the operation of said actuating mechanism; means for latching said tens transfer devices in an ineffective position, and means functioning in response to the operation of a said key for moving a said tens transfer device into engagement with said latching means to be latched thereby.

45 5. In a calculating machine having an accumulator including tens transfer devices, an actuating mechanism for said accumulator mechanism, and keys for controlling the operation of said actuating mechanism; means for latching said tens transfer devices in an ineffective position, means functioning in response to the operation of a said key for moving a said tens transfer device into engagement with said latching means to be latched thereby to foil a carrying action, and means operable to release said tens transfer device from said latching means after a carrying action has been foiled.

60 6. In a calculating machine having an accumulator including tens transfer devices, an actuating mechanism for said accumulator mechanism, and keys for controlling the operation of said actuating mechanism; means for latching said tens transfer devices in an ineffective position, means functioning in response to the operation of a said key for moving a said tens transfer device into engagement with said latching means to be latched thereby, and selectively operable means for rendering said last named means operative or inoperative.

65 7. In a calculating machine having an accumulator including tens transfer devices, an actuating mechanism for said accumulator mechanism, and keys for controlling the operation of said actuating mechanism; means for latching

said tens transfer devices in an ineffective position, means functioning in response to the operation of a said key for moving a said tens transfer device into a position to be latched by said latching means to foil a carrying operation thereby, selectively operable means for rendering said last named means operative or inoperative, and means operable by said actuating mechanism after said tens transfer device has been engaged with said latching mechanism for returning said selectively operable means and the key responsive means rendered operative thereby to inoperative position.

8. In a calculating machine having an accumulator including tens transfer devices, an actuating mechanism for said accumulator mechanism, and keys for controlling the operation of said actuating mechanism; means for latching said tens transfer devices in an ineffective position, means functioning in response to the operation of a said key for moving a said tens transfer device into engagement with said latching means to foil a carrying operation thereby, selectively operable means for rendering said last named means operative or inoperative, means operable by said actuating mechanism after said tens transfer device has been engaged with said latching mechanism for returning said selectively operable means and the key responsive means rendered operative thereby to inoperative position, and means operable to release said tens transfer device from said latching means after an attempted carrying operation has been foiled.

9. In a calculating machine having an accumulator including tens transfer mechanisms, actuating mechanism for said accumulator, and depressible keys for controlling said actuating mechanism; settable means operable in response to the depression of a said key for preventing the operation of a said tens transfer mechanism, and means included in said actuating mechanism shiftable into blocking relation to said settable means to prevent the setting of the same during operation of said actuating mechanism.

10. In a calculating machine having an accumulator including tens transfer devices, actuating mechanism for said accumulator, depressible keys for controlling said actuating mechanism, means for zeroizing said accumulator, and manually operable mechanism for actuating the zeroizing means; means for latching said tens transfer devices in ineffective position, normally inoperative means operable upon depression of a said key for moving a said tens transfer device into engagement with said latching means to be latched thereby, settable means for rendering said tens transfer device moving means operative, and means actuated by said manually operable mechanism to release said latching means and move said tens transfer device moving means and said settable means to an inoperative position.

11. A calculating machine having, in combination, a multiple order accumulator mechanism including automatic carrying mechanism, actuating mechanism for each order operable to actuate the corresponding order of accumulator mechanism in variable degrees of actuation, a denominational order of digital keys for each order of actuating mechanism operable to determine the digital setting of the mechanism of that order, normally inactive carry cut-out mechanism individually associated with each order of accumulator mechanism operable

5 to disable the carrying mechanism of the order, a subtraction control device, and means operated by said control device for simultaneously conditioning all of said cut-out mechanisms for operation by their associated digital keys.

12. In a calculating machine having a multiple order accumulator including a tens carrying device for each order, actuating mechanisms for the accumulator, and denominational orders of keys for controlling the actuating mechanism; the combination of normally inactive subtraction mechanisms operable to prevent the carrying of tens by the carrying devices of the respective orders, means actuated by the keys for operating the subtraction mechanism of the corresponding orders, and a single manipulative member operable to condition said subtraction mechanisms for such operation by the keys.

13. In a calculating machine having a multiple order accumulator including a tens carrying device for each order, actuating mechanisms for the accumulator, and denominational orders of keys for controlling the actuating mechanism; the combination of normally inactive subtraction mechanisms operable to prevent the carrying of tens by the carrying devices of the respective orders, means actuated by the keys for operating the subtraction mechanism of the corresponding orders, a single manipulative member operable to condition said mechanisms for such operation by the keys, and means for restoring the conditioned subtraction mechanisms to inactive position upon the actuation of any one of the keys.

14. In a calculating machine having a multiple order accumulator with a series of automatic tens carrying mechanisms and a foil means for each said mechanism adapted when actuated to disable the same, a plurality of ordinal columns of value keys, ordinal means actuated selectively in response to the depression of said keys for actuating said accumulator, manual settable means for conditioning the foil means of all said tens carrying mechanisms for actuation, the selectively actuated ordinal means being operable to actuate the conditioned foil means corresponding to the column in which the depressed key is found, and means responsive to the depression of said key to restore the conditioned foil means to normal condition.

15. In a calculating machine having a multiple order accumulator with a series of ordinal automatic tens carrying mechanisms and a foil means for each such mechanism, a plurality of ordinal columns of value keys, manually settable means for conditioning the several foil means for operation for purposes of subtraction, means operative in response to the depression of a value key in a selected one of said columns to actuate the conditioned foil means of the order corresponding to the selected column, and means responsive to the depression of said key for restoring the conditioned foil means to normal condition.

16. In a calculating machine having a multiple order accumulator with a series of ordinal automatic tens carrying mechanisms and a foil means for each such mechanism adapted when actuated to disable the same, a plurality of ordinal columns of value keys, manually settable means for conditioning all of said foil means for actuation, a series of ordinal elements selectively shiftable upon the depression of any one of said keys in accordance with the column in which said key is found to actuate the conditioned foil means of its corresponding tens carrying mechanism, and means responsive to the depression of said key for

restoring the conditioned foil means to normal condition.

17. In a calculating machine having a multiple order accumulator with automatic ordinal tens carrying means and a plurality of ordinal columns of value keys, a series of ordinal actuator elements movable in response to the depression of said keys selectively in accordance with the column in which the depressed key is found for operating said accumulator, subtraction means for rendering said tens carrying means ineffective including a series of ordinal motion transmitting elements shiftable into operative association with respective ones of said actuator elements for movement thereby, means operable manually to shift said motion transmitting elements simultaneously into operative association with said actuator elements, and means responsive to the depression of any of said value keys for withdrawing the motion transmitting elements from operative association with their respective actuator elements.

18. In a calculating machine having a multiple order accumulator with a series of automatic tens carrying mechanisms and a foil means for each said mechanism adapted when actuated to disable the same, a plurality of ordinal columns of value keys, ordinal means actuated selectively

5 in response to the depression of said keys for actuating said accumulator and each including a member shifted through a predetermined stroke, manually settable means for conditioning the foil means of all said tens carrying mechanisms for actuation, the selectively actuated ordinal means being operable through its shiftable member to actuate the conditioned foil means corresponding to the column in which the depressed key is found, and power actuated means operable in response to the depression of said key for restoring the conditioned foil means to normal condition.

19. In a calculating machine having an accumulator including tens transfer devices, an actuating mechanism for said accumulator mechanism, and keys for controlling the operation of said actuating mechanism; each of said transfer devices including a carrying pawl, and means functioning in response to the operation of a said key for holding the corresponding carrying pawl in ineffective position, said means including a latch tooth on the carrying pawl, a spring actuated latch element for coaction with said tooth, and a key responsive member for shifting said pawl to carry its latch tooth into engagement with said element.

JOSEPH A. V. TURCK.
